PAPER EQUIPMENT FOR ACCOUNTING MACHINES

Robert L. Muller, Detroit, Mich., assignor to Burroughs Adding Machine Company, Detroit, Mich., a corporation of Michigan

Application May 12, 1932, Serial No. 610,788

65 Claims. (Cl. 235—60)

This invention relates to paper equipment for accounting machines. It is directed particularly to an improved control for paper carriages that will enable greater speed to be obtained in certain classes of work such as the writing of public utility bills.

In making out certain classes of bills, such as public utility bills, it is often necessary to print an item several times on different portions of the bill, some portions going to a different person in the accounting system and one or more portions going to the customer. This duplicate printing is usually accomplished by having a machine operate through a series of automatic operations during which the paper carriage is tabulated from one column to another across the machine in a given direction. Before a second series of items can be entered, the carriage must be returned across the machine to its original position, line spaced, and then actuated through the second series of operations. The return of the carriage across the machine is somewhat slow and the time required for the return is lost.

The present invention contemplates an improvement in which, instead of returning the carriage across the machine in order to get it in position for a second series of items, the second, or succeeding, series of items is entered immediately and the carriage is then returned step by step during which time the second series of items is printed. In other words, operations may be started with the carriage at either end of its travel and the carriage stepped across the machine away from the position it happens to be in. No time is lost during the carriage return. This saving in time is important in industries where hundreds of bills are written per day.

The general object of the invention is to provide an improved paper equipment for accounting machines.

A more particular object is to provide an improved carriage control mechanism that will enable a paper carriage to not only be moved step by step across the machine in one direction, but to be returned step by step in the opposite direction.

A further object is to provide a machine of this character in which the machine will go through a series of operations automatically without requiring any attention on the part of the operator, during which operations the carriage will be automatically stepped across the machine in either direction depending upon its position at the time operations are started.

Another object is to provide a construction in

which, in a step-by-step return of a paper carriage, certain predetermined columns may be skipped.

A further object is to provide a carriage return mechanism in which the carriage may be automatically arrested in an intermediate position, the machine operated with the carriage in this position, and the return of the carriage then automatically completed without any attention on the part of the operator.

Other objects are:

To increase the speed of the automatic carriage return mechanism by setting it into operation more quickly than has heretofore been the case;

To provide improved means for automatically line spacing the platen at the end of the travel of the paper carriage in either direction, and between the end of one series and the beginning of another series of automatic operations of the machine;

To provide for improved control of non-adding and total-taking so that items or totals may be printed during each operation of a series of automatic operations of the machine without causing incorrect registration in the registering mechanism.

Still other objects will appear from the following specification and drawings.

An embodiment of the invention is shown in the drawings in which;

Figures 1 and 2 illustrate examples of the work that the machine is adapted to perform.

Fig. 3 is a right side elevation of a machine having the invention applied thereto, the parts being shown in normal addition condition.

Fig. 4 is a partial right side elevation similar to Fig. 3 with the parts in the position they occupy with the machine conditioned for operation immediately after the carriage has moved to its last column in its movement from right to left across the machine, viewing the machine from the front.

Figs. 5 and 6 are detail views of portions of the automatic repeat mechanism.

Fig. 7 is a detail view of a portion of the mechanism that controls the automatic line spacing of the platen and the normalizing of the repeat mechanism, the parts being shown in the position they occupy with the carriage in the same position as described for Fig. 4.

Fig. 8 is another partial right side elevation of the machine with the parts in the position they occupy when the machine is conditioned for a series of operations in which the carriage is

to be returned step by step across the machine.

Fig. 9 is a detail view of certain of the controls in the positions they occupy for the first machine operation after the carriage has reached its last 5 columnar position to the right after its movement from left to right across the machine viewing the machine from the front.

Fig. 10 is a left side elevation of the machine with the parts in normal position.

Fig. 14 is a detail view of the carriage control for the automatic repeat mechanism.

20 Fig. 15 is a rear view of the controls for the carriage return mechanism which automatically enable and disable said mechanism whereby the carriage is returned in a step by step manner, the parts being shown in normal position.

25 Fig. 16 is a front view of the controls shown in Fig. 15.

Fig. 17 is a front view of the controls for the carriage return mechanism showing the parts in the position they occupy after they have been 30 positioned to condition the carriage return mechanism for operation.

35 Fig. 18 is a rear view of the controls for the carriage return mechanism showing particularly the disabling mechanism for disabling the carriage return mechanism.

40 Fig. 19 is a view similar to Fig. 18 showing the position of the parts after the carriage return mechanism has been disabled and the carriage has reached its position of rest in the column in which it is stopped.

45 Fig. 20 is a rear view of the machine with the carriage return unit removed in order to show the carriage controls more clearly.

50 In order that the mechanism and the purpose of the various portions thereof may be more clearly understood as the description progresses, a brief explanation will first be given of certain examples of work that may be performed.

Examples of work

55 Fig. 1 shows a public utility bill having four sections separable from one another, each bearing a list of the same items. After the bill is written, the "accounting stub" and the "collection stub" are separated from the bill and they go to separate departments. The "customer's bill" and the "payment stub" are both sent to the customer. When the customer pays his bill the "customer's bill" portion is receipted and returned to the customer and the "payment stub" is detached for the use of the cashier.

60 This bill requires that any given item be printed four times. The usual practice has been to supply the machine with an "automatic repeat print" mechanism which causes it to go through a series of operations during which the carriage is tabulated so that the item is repeated in different predetermined columnar positions of the carriage. After the series of operations has been completed 65 the carriage is returned across the machine by hand or by power to its original starting position after which a second entry is made and the machine is operated through a second series of operations.

70 In the present machine, the carriage is allowed

75 to remain in the last columnar position to which it has been moved by the first series of operations. The platen is automatically line spaced and the second series of operations is started with the carriage in the position it happens to occupy at the end of the first series. The second series of items is printed while the carriage is returned across the machine.

80 In Fig. 1 the first series of items is for "service \$5.00". The amount (\$5.00) is entered on the 10 keys with the carriage in its first columnar position, it is printed in the first column, and the machine goes through a series of automatic operations resulting in printing the item \$5.00 in the second, third, and fourth columns. After 15 the \$5.00 is printed in the last column, the platen is line spaced and the next series of entries for "toll \$.50" begins on the "accounting stub" and continues across the bill to the left. The next series of operations is to print the total of the 20 two items. The platen is line spaced before the next series of operations, the total key is depressed, and the machine is then operated through a third series of operations to print the total on each of the stubs. The carriage now 25 occupies its left hand position, viewing the machine from the front, and, under former practice, the carriage would be returned to the right before another bill was inserted. In the present machine, the carriage is allowed to remain in the 30 left hand position and the second bill is inserted immediately after the first and without changing the position of the carriage.

35 Fig. 2 represents a second bill in which the first item is for service \$5.00. This bill is inserted while the carriage is in its left-hand position so that the first entry is printed on the "accounting stub". The machine is then put through a series of operations that prints the item on each of the sections of the bill as the carriage 40 moves to the right after which the platen is automatically line spaced and the second item is entered, namely, "Toll \$.50". The machine goes through a second series of operations to print the second item on each part of the bill while the carriage is moving to the left after which the platen is line spaced again and a third item is entered, namely, "Extension \$1.00". This is 45 printed on each portion of the bill while the carriage is returning to the right after which the platen is again line spaced and a fourth item, 50 namely, "Advertising \$2.00" is entered, and the machine given a fourth series of operations as the carriage moves to the left. This leaves the paper carriage in its left-hand position as viewed 55 from the front. It is now desired to take a total. The platen is automatically line spaced, the total key depressed, and the machine operated through a fifth series of operations which results in printing the total on each part of the stub of the bill 60 as the carriage returns step by step to the right.

65 It will be understood that it is not desirable to enter each of the items in the register for each of the operations of the machine although it is necessary to enter the items during one of the 65 operations. This calls for a control that will result in entering the items once in a register no matter in which direction the carriage is traveling. Likewise, it is not desirable to clear the register for the printing of each total, but 70 it is desirable to clear it after the last totaling operation has been performed. It is therefore necessary to cause the machine to go through subtotaling operations in all but its last total printing operation and this must occur no mat- 75

ter whether the carriage is moving from left to right or right to left.

General machine features

- 5 The invention is shown applied to a Burroughs calculating machine, the general features of which are well known and described in numerous patents so that only a brief outline of them will be given here.
- 10 The machine has a plurality of depressible amount keys 10 (Fig. 3) controlling the differential positions of actuator racks 11. Associated with the actuator racks are type segments 12 which are differentially positioned with the actuator racks for the purpose of printing the items corresponding to the actuator rack positions.
- 15 Associated with the actuator racks is an addition-subtraction register 13 of the tumbling type in which items entered on the amount keys may be added or subtracted. Also associated with the racks are a plurality of counters of the interspersed-pinion type of which one is shown numbered 14 in Fig. 3.
- 20 The register 13 is rocked into and out of engagement with the actuator racks by means of a pitman 15 (Fig. 10) connected to a three-armed lever 16 carrying studs 17 and 18. The three-armed lever 16 is rocked by means of a pass-by pawl 19 carried on the end of an arm 20 which is oscillated by the shaft 21 at each operation of the machine. The arrangement is such that the register is normally in engagement with the actuator racks. At the beginning of the forward stroke of the machine the pass-by pawl 19 engages the stud 17 and rocks the register out of engagement with the racks so that the racks are differentially positioned while the register is out of engagement with them. At the beginning of the return stroke the pass-by pawl 19 engages a stud 18 and rocks the register into engagement with the actuator racks so that the item entered on the amount key is registered during the return stroke of the machine.
- 25 The register may be non-added by disabling the pass-by pawl 19 to prevent it from engaging the stud 18 upon the return stroke of the machine. This is accomplished by means of a pivoted member 22 urged clockwise by a spring 23 to an inoperative position but movable to the operative position of Fig. 10 for disabling the pawl 19 by a pivoted member 24 which is moved by a lever 25 carrying a stud 26 which operates on a raised portion 27 of member 24. Lever 25 is controlled by one arm 28 of a pivoted yoke 29 having another arm 30 positioned to be engaged by one or more rolls 31 on a paper carriage.
- 30 The machine has a total key T which, when depressed downward, conditions the mechanism for total-taking. Depression of the key T lowers the pitman 15 so as to disconnect it from the stud 32 on the register frame 33 and position it for connection to the stud 34. If at the beginning of the forward stroke of the machine
- 35 the register is already in engagement with the racks, the forward movement of the pitman 15 will not rock the register out of engagement, but, if for any reason the register is not in engagement with the racks, the forward movement of the pitman rocks the register frame 33 counterclockwise to move register 13 into engagement with the actuator racks instead of moving it out of engagement as would occur if the total key were not depressed. The actuator racks are then
- 40 differentially positioned by the register pinions,

suitable stops being provided for arresting the register pinions in "0" position. At the beginning of the return stroke of the machine the rearward movement of pitman 15 rocks the register out of engagement with the actuator racks instead of into engagement with them as in addition so that the pinions remain in "0" position, i. e., the register is left clear.

45 A traveling paper carriage 40 is provided supporting a platen 41 which is rotatably mounted so that it may be line spaced. The carriage is mounted to travel back and forth across the machine and it is urged from right to left as viewed from the front of the machine by means of a spring drum 42 and tape 43 as shown in Fig. 13. 10 The carriage has the usual tabulating bar, shown in Fig. 20, carrying a plurality of tabulating dogs 44 (Fig. 13) adapted to engage a stop 45. The carriage is tabulated from one column to another by momentarily rocking the bar carrying the tabulating dogs 44 so that the dog 44 immediately engaging stop 45 is raised above the stop. This permits the carriage to move under the influence of its spring until the next dog strikes the stop, the bar carrying the dogs having, in the meantime, been returned. The bar may be rocked by hand or automatically by the power of the machine.

20 The stop 45 is cushioned by being connected by a link 46 to one arm 47 of a yoke 48 pivoted at 49 to the back panel. The other arm 50 of this yoke is connected by a link 51 to the piston 52 of a dash pot 53. The details of this cushioning mechanism are described in Muller Patent No. 1,757,134.

25 The paper-positioning and paper feeding means of the carriage are of the general type shown in Muller Patent No. 1,787,489 and need not be explained in this application.

30 The machine is provided with a motor drive comprising a motor 55 (Fig. 3) controlled by a clutch in housing 56. When the clutch is engaged the motor gives the machine a forward and return stroke of operation by oscillating the shaft 57 (Fig. 10) to which is fixed a crank 58 connected by a link 59 to a wrist pin 60 on a crank 61 connected to a shaft driven by the motor.

35 The clutch 56 is conditioned to cause the motor to give the machine a stroke of operation by depressing a motor bar 62 (Fig. 4) connected to two pivoted levers 63 and 64. Depression of the motor bar 62 rocks lever 63 counterclockwise and this lever, acting through a spring 65, raises a link 66 which conditions the clutch to cause the motor to give the machine a stroke of operation. The shaft 57 (Fig. 3), which is oscillated during each operation of the machine, is connected by a crank 55 and connecting rod to a full stroke sector 67 carrying a stud 68 positioned to engage a projection on link 66 as the machine is operated. During the forward stroke of the machine the full stroke sector is rocked counterclockwise and the stud 68 engages link 66 to move it downward to disconnect the clutch. This motor drive and the control therefor by means of the motor bar 62 are described in detail in Vincent Patent No. 866,750.

40 The motor also drives an automatic carriage return mechanism indicated generally at 69 (Figs. 3 and 10) which, except for the improvements herein shown and described, is shown and described in detail in Rinsche Patent No. 1,580,534.

Automatic repeat mechanism

45 The machine is provided with an automatic repeat mechanism of the general type shown in Patent No. 1,397,774. Although this mechanism is well known, its close association and combina-

tion with the present invention, together with the modifications that have been made in the control thereof, require that the mechanism be explained.

When the motor bar 62 is depressed, a latch 70 on the lever 64 normally engages over a stud 71 on lever 63 to hold the motor bar depressed. However, in normal, non-repeat, operations, the latch 70 is released by means of a slide 72 carrying the lug 73 adapted to engage the upper end of the latch 70. The slide is moved by the upper end of a pivoted lever 74 whose lower end carries a roller stud 75 adapted to be engaged by a pass-by pawl 76 on an arm 77. This pass-by pawl is mounted so that, normally, during the clockwise movement of arm 77, the pawl passes below the roller stud 75 and, then, upon the return movement of arm 77, the pawl cams stud 75 to rock the lever 74 counterclockwise. When the lever 74 is so rocked it releases the latch 70 which, in turn, releases the motor bar for return to normal. The lever 74 also carries a releasing bail 78 for releasing the latches of the depressed keys so that the keys will be normally released for movement to normal during the return stroke of the machine.

Repeat operations are obtained by preventing the pass-by pawl 76 from moving below the stud 75 during the clockwise movement of arm 77. This condition is brought about by moving a slide 80 rearward far enough to bring a shelf 81 on the slide beneath a stud 82 on the arm 77 so that the arm cannot descend to the full limit of its movement. The slide 80 is connected through a spring 83 (Fig. 8) and by a pin and slot connection to one arm 84 of a pivoted bell crank lever having another arm 85 extending rearwardly and positioned under the end of one arm of a bell crank lever 86, pivoted on the back plate of the machine (Fig. 13.) This lever is connected by a link 87 to one arm 88 of a pivoted yoke 89 having a carriage control arm 90 whose upper end is positioned in the path of a roller 91 carried by a shaft 92 on the paper carriage. One of these rolls may be provided for any one or more columns of the carriage. In the machine shown a roll is provided for each column 91, 91², 91³, and 91⁴ and the machine is arranged for four column work.

When the roll 91 engages the end of arm 90 it rocks the yoke 89 clockwise as viewed in Fig. 13. This rocks the bell crank lever 86 counterclockwise and moves the arm 85 downwardly. Referring to Fig. 8, the downward movement of lever 86 rocks the bell crank lever 84-85 clockwise which pulls the slide 80 rearwardly to position the shelf 81 under the stud 82. Accordingly, when one of the rollers 91 on the carriage engages the arm 90, the repeat mechanism is conditioned for repeat operation.

When the motor bar 62 is latched downward in the position of Fig. 4, the link 66 is, nevertheless, moved down at each operation of the machine by the stud 68 on the full stroke sector 67. This downward movement is permitted by the pin and slot connection between the upper end of the link 66 and the lever 63. The downward movement of the link 66 merely tensions the spring 65. After the link 66 is moved downward by the full stroke sector, its full return is temporarily delayed by means of a latch 92 which moves over a stud 93 on the link 66 as shown in Fig. 6. This temporarily prevents the link 66 from rising again but the link must be raised in order to give the machine another stroke of operation. The link is released by means of a hook-shaped extension 94 (Fig. 4) on the slide 80, which ex-

tension is positioned to engage a stud 95 on the latch 92.

Referring now to Figs. 13 and 14, it will be observed that the end of arm 90 which controls the movement of the repeat slide 80 has a pointed portion 96 and an inclined portion 97 (Fig. 14). As the carriage moves to the left, which would be to the right in Fig. 13, the roll 91 passes over the high point 96 on the arm 90 and moves the repeat slide 80 farther rearwardly than is necessary for repeat operations. This extra movement of the slide causes the extension 94 (Fig. 4) to engage stud 95 and moves the latch 92 to a position to release the link 66 so that the latter will move upward under the influence of its tensioned spring 65. After link 66 has moved upward it is releasably held in its upper position by a scissors latch, as shown in Fig. 5, said latch including the latch 92 and an associated member connected together by a spring. This extra movement of the repeat slide 80 is only a momentary one. As soon as the roll 91 passes over the high point 96, the repeat slide 80 returns forward under the influence of its spring 98 (Fig. 8), but it does not move forward to a released position. It is to be noted that when the carriage is at rest in a columnar position provided with a repeat roll as shown in Fig. 13 and in dotted lines in Fig. 14, the roll engages the inclined face 97 of arm 90 so as to hold the arm downward. This holding down of the arm 90 holds the repeat slide 80 rearward in its repeat position and this point must be kept in mind in connection with the subsequent description of the operation of the machine.

In order that the operation of this automatic repeat mechanism may be clearly visualized, a sequence of operations will be followed through. In this connection it must be remembered that the paper carriage moves from one column to another at the end of the return stroke of operation of the machine, that is, the machine operates to perform its calculating and printing functions after which the carriage automatically moves to the next column so as to be in position for the next machine operation. In the present machine a repeat roller is provided in the first column so that when the machine stands in its normal unoperated position in column No. 1, the lever arm 90 of yoke 89 is held down by a repeat roller 91 on the carriage.

Assume, now, that the motor bar 62 is depressed. As soon as it is depressed it is latched in depressed position by latch 70. Depression of the bar raises the link 66 and causes the motor 55 to give the machine a stroke of operation. During the latter part of the forward stroke of the machine the link 66 is moved downwardly by stud 68 and, on the return stroke, it is held from complete return movement by the latch 92. The 60 arm 77 is rocked clockwise as viewed in Fig. 4 during the forward stroke, but the pass-by pawl 76 does not move below the roller stud 75. On the return stroke of the machine the stud 68 on the full stroke sector releases link 66, but the 65 latter cannot fully rise immediately because of the latch 92. The return stroke does not cause the pass-by pawl 76 to rock lever 74, and, consequently, the latch 70 is not released, nor are the 70 depressed keys released. At the end of the return stroke of the machine the carriage is released and it moves to the next or No. 2 column under the influence of its spring. As it moves to the No. 2 column the roll 91² for the second column engages the high point 96 of the lever 90 and 75

moves it so as to move the repeat slide 80 rearwardly sufficiently to move latch 92 from over the stud 93. The link 66 then completes its upward movement under the influence of its spring 5 65 so as to condition the clutch to cause the motor to give the machine another stroke of operation. During the time this occurs the carriage has been moving to its home position and the roll 91² moves over the high point 96 of arm 91 10 to the inclined portion 97 so as to hold the repeat slide 80 in position to cause a second repeat operation.

The machine thus continues to operate automatically as long as repeat rolls 91², 91³, 91⁴, etc. 15 are provided to keep the repeat slide 80 in its rearward position.

When the carriage moves to its last columnar position, which is the fourth column in the present machine, it is desired to stop the automatic 20 repeat operations of the machine. However, the machine must be operated in the fourth column.

Referring to Fig. 20, it will be observed that 25 the roll 91⁴, which is operative when the carriage moves from its third to its fourth columnar position, is located in a slightly different position than the rolls for the other columns. It is positioned so that, while it will move the arm 90 down as the carriage moves from its third to its fourth columnar position by reason of the roll engaging the high point 96 of the arm, it passes beyond the arm when the carriage reaches its final position in the fourth column. In other words, 30 the arm 90 is not held down when the carriage is in the fourth column. The result is that, as the carriage moves from its third to its fourth columnar position, the arm 90 is moved downwardly by roll 91⁴ so as to move the repeat slide 80 rearwardly to release the latch 92 to enable the link 66 to move up to give the machine a stroke of operation in the fourth column, but arm 90 and repeat slide 80 are immediately released and they move back so that the repeat slide is in its forward non-repeat position. The 35 result is that, as the machine is operated in the fourth column, the pass-by pawl 76 moves below the roller stud 75 upon the forward stroke of the machine. Then, upon the return stroke of the machine, the lever 74 is rocked which releases the 40 depressed keys and releases latch 70 thereby enabling the motor bar 62 to return to normal to condition the controls so that no succeeding automatic operation of the machine will occur.

In this manner, the motor driving means is 45 caused to actuate the machine through a series of automatic operations after which the machine is automatically stopped when the carriage reaches its last columnar position which, in the example illustrated, is the fourth column.

50 A delayed action mechanism is provided to prevent misoperation of the automatic repeat mechanism, particularly in the fourth column. For example, when the carriage is moving from its third to its fourth column, the roll 91⁴ releases the latch 92 and enables the link 66 to move up earlier than in the other columns. In other words, the machine is conditioned for a stroke of operation a little earlier than in the other columns. This might cause a stroke of operation 55 of the machine before the carriage has reached its final position of rest and means is provided for insuring that no such thing occurs.

Referring to Fig. 13 and to the cushioning mechanism for the carriage, it will be observed 60 that the arm 41 of yoke 48 is connected by a pin

and slot connection to a link 100 which, in turn, is connected to a pivoted bell crank lever 101. This bell crank rests against one arm of a bell crank 102 (Fig. 4) urged counterclockwise by a spring 103 (Fig. 4). The other arm of bell crank 102 is connected by a link 104 to a pivoted lever 105 having a lateral lug 106 on its upper end adapted to engage over a shoulder 107 on the link 66.

When the link 66 is moved downwardly, as it 10 is during each operation of the machine, the lug 106 passes over the shoulder 107 and blocks the full return upward movement of the link until the lever 105 is rocked clockwise. The lever 105 is not rocked clockwise until the carriage is at 15 rest because the lever is moved only when the piston 52 (Fig. 13) is moved into the dash pot by reason of the carriage moving into engagement with the tabulating stop. When the carriage does engage and move the tabulating stop 45, the lever 20 47 is rocked counterclockwise, which rocks lever 101 in the same direction. This rocks lever 102 (Fig. 4) clockwise, and the latter, acting through link 104, rocks the lever 105 clockwise to release link 66. This release occurs after the carriage 25 has reached a position of rest in the columnar position to which it has been moved.

Referring to Fig. 3, it will be observed that the lug 106 on the lever 105 is positioned with reference to the shoulder 107 so that it permits a 30 slight upward movement of the link 66 before the shoulder contacts the lug. This enables the stud 93 on link 66 to move in front of the latch 92 to prevent the latch from returning to the latched position of Fig. 6, after said latch is released by 35 reason of a roller of the 91 series passing by the high point on the arm 90. The release of latch 92 is a very momentary release and, if the link 66 were held down in its extreme lower position, the latch 92 would move back to latching position 40 and the delayed action mechanism would result in preventing another operation of the machine. However, with the construction just explained, this is avoided by the slight upward movement 45 of the link.

Automatic line spacing at end of carriage movement in one direction

After the machine has been given a series of 50 automatic operations and stopped with the carriage in its left-hand position as viewed from the front of the machine (column 4, Fig. 1), it is desirable to have the platen line spaced before the next series of operations begins. This is necessary in order that the second line of entries 55 shall be below the first. Provision is made for accomplishing this result automatically after the carriage has reached its last columnar position to the left and before it returns to the right.

Pivoted to the full stroke sector 67 (Fig. 8) 60 and extending rearwardly is a link 110 carrying a stud 111 adapted to operate in an L-shaped slot 112 in a pendant member 113 pivoted at 114. The link 110 is urged counterclockwise by a spring 115 connected between it and the member 113 so 65 that the stud 111 normally travels in the long horizontal portion of the L-shaped slot 112 and has no effect on member 113. The stud 111 is moved into the short vertical portion of the L-shaped slot 112 by means of one arm 116 of a 70 V-shaped lever pivoted at 117. The other arm 118 of this V-shaped lever extends upwardly to a position behind a stud 119 on the arm 84 of bell crank lever 84—85 forming a part of the train 75

of connections for the automatic repeat mechanism.

In columnar positions of the carriage where the automatic repeat mechanism is conditioned for repeating, the parts occupy the position illustrated in Fig. 8. The V-shaped lever 116-118 is held upward by the influence of the spring 115 acting through stud 111 on said lever and said lever may occupy the position of Fig. 8 because the bell crank lever 84-85 carrying stud 119 is held by one of the repeat rolls on the carriage in the position of Fig. 8.

When the carriage moves from its third to its fourth columnar position the bell crank lever 84-85 is no longer held by a carriage roll and it is rocked counter-clockwise by its spring 98 which results in the automatic repeat mechanism being disabled as previously explained. As bell crank 84-85 is rocked counterclockwise, its stud 119 rocks the V-shaped lever 118-116 in the same direction and the link 110 is moved downwardly to move the stud 111 into the vertical portion of the L-shaped slot 112 as illustrated in Fig. 4. The spring 98 overcomes spring 115 in this movement. This occurs as the carriage moves from its third to its fourth columnar position so that the parts are conditioned before the machine is given a stroke of operation in the fourth column. It is to be noted that the connections just described, which operate the line spacing mechanism, as will be later explained, are conditioned for operation under the control of the carriage and as an incident to the disablement of the repeat mechanism.

As the machine is operated in the fourth column the full stroke sector 67 is rocked counterclockwise during the forward stroke and it pulls the link 110 forward. The stud 111 being in the vertical portion of the L-shaped slot 112, the pendant member 113 is rocked from the position of Fig. 4 to that of Fig. 7. In the normal position of this pendant member 113 a stud 125 on a vertically slidable member 126 occupies a notch 127 in the pendant member, said slide 126 being urged upward by a spring 128. When the pendant member 113 is swung from its Fig. 4 to its Fig. 7 position, said member, acting on stud 125, cams the slide 126 downward. The slide 126 has a rearward extension 129 provided with a stud 130 operating in an inclined slot 131 (Fig. 13) in the upper end of a lever 132 pivoted at 133 to the back plate of the machine. Connected to the lever 132 is a link 134 which extends to the right, as shown in Fig. 13, and is provided near its right hand end with an upstanding lug 135 engaging behind a member 136 pivoted on the back plate and positioned to engage a pawl 137. The pawl 137 is pivoted on a member 138 that is reciprocated up and down during each operation of the machine, said member forming a part of the usual line spacing mechanism on a Burroughs machine. Normally, the up and down movement of member 138 is an idle one but it may be made effective for line spacing by connection to a second slide 139 connected at its upper end to the line spacing bail 140. This connection is effected by pawl 137 which has a lug 141 adapted to engage a notch in the slide 139. The pawl 137 is moved clockwise from its Fig. 13 position to an engaged position during the forward stroke of operation of the machine immediately following the movement of the carriage from its third to its fourth columnar position. This movement is effected as follows:

As the paper carriage reaches its fourth col-

umnar position, the repeat mechanism is released which releases the V-shaped lever 118-116 which moves the stud 111 into the vertical portion of slot 112. As the machine is operated the link 110 is moved forward and the pendant 5 113 is rocked to its Fig. 7 position which cams the slide 126 downward. The stud 130 on slide 126 causes the lever 132 (Fig. 13) to be rocked clockwise and this thrusts the link 134 to the right. The lug 135 on link 134 moves the pivoted member 136 and its rocks the pawl 137 clockwise to connect the slides 138 and 139 together. This occurs during the forward stroke 10 of the machine in order to condition the line space mechanism for operation during the return stroke. 15

Accordingly during the operation of the machine immediately following the movement of the carriage from its third to its fourth column, the connections for line spacing the platen are automatically conditioned under control of the 20 carriage and as an incident to the disablement of the repeat mechanism and the platen is automatically line spaced by power derived from operation of the machine. This line spacing does not occur until near the end of the return stroke 25 of said machine operation in order that printing may take place before the platen is moved.

Automatic step by step return of carriage

After the carriage has reached its fourth columnar position and after the machine has been operated and the platen line spaced, the machine stops. A second item is then entered, the machine is given a stroke of operation in the fourth column, and the carriage is then automatically returned from column to column until it reaches its first columnar position again. During this return of the carriage, the machine is operated automatically in each of the columnar 35 positions of the carriage and then stopped after 40 it operates in the No. 1 carriage position. Although the return in the machine illustrated is from column to column through four columnar positions, the number of columns can be varied 45 as desired and one or more of them can be skipped as will later appear. 45

In order for the machine to be actuated through a second series of automatic operations, it is necessary to recondition the automatic repeat mechanism, but it will be remembered that when the carriage is in its fourth columnar position there is no repeat roll in contact with the arm 90 and hence the automatic repeat mechanism is not conditioned for repeating. Accordingly, it becomes necessary to provide a means for conditioning said repeat mechanism in connection with the automatic return of the carriage. 55

A return motor bar 150 is provided as illustrated in Figs. 3 and 4. The stem 151 of this bar has a rearward extension 152 positioned over a stud 153 on a stem of the regular operating bar 62 so that, when the return bar 150 is depressed, the regular motor bar 62 is also depressed as illustrated in Fig. 8.

An interlock between the bars is provided comprising a bell crank lever 154 pivoted on the extension 152 of stem 151 and provided with a forked end engaging over the stud 153. This lever cooperates with a stationary stud 155 on the machine frame. When the return bar 150 is depressed to the position of Fig. 8, the parts occupy the position there shown with the regular motor bar 62 locked in depressed position. Should the return motor bar start to rise again, the bell crank lever 154 may be turned slightly, 75

but it can move only a limited distance because it will engage the stud 155 and this will block further upward movement of the return motor bar. This insures that the return motor bar will be locked in depressed position as long as the regular bar is locked in this position.

This interlock also prevents the return motor bar from being depressed when the regular motor bar has been depressed. When the regular motor bar is depressed, the bell crank lever 154 is rocked clockwise to the position of Fig. 4 where the lower portion of the lever is over the stud 155. If an attempt is made to depress the return bar 150, the end of the lower branch of lever 154 engages the stud 155 and blocks downward movement of said bar.

The stem 151 of the return motor bar 150 carries a square stud 156 near its lower end positioned to engage one end of a lever 157 pivoted at 158 to a stationary support. The lever 157 is urged into engagement with the stud 156 by a spring 159 which also acts on one end of a lever 160 pivoted to the machine frame. The other end of lever 160 acts on the stem 151 of the return motor bar to urge said motor bar upward toward undepressed position.

The lever 157 is connected at its rear end to a second lever 162 pivoted on the stationary pivot 114. This lever has a cam extension 163 positioned in front of the stud 119 on the bell crank lever 84—85, which forms a portion of the train of connections for conditioning the automatic repeat mechanism for operation.

When the return motor bar 150 is depressed, the lever 157 is rocked counterclockwise. This rocks the lever 162 clockwise and the cam faced end 163 of the latter engages the stud 119 to rock the bell crank lever 84—85 clockwise. This moves the repeat slide 80 rearwardly and positions the shelf 81 under the stud 82 so that the automatic repeat mechanism is conditioned for operation. At the same time that this automatic conditioning takes place, the machine is conditioned for operation because depression of the return motor bar depresses the regular motor bar 62 to cause the motor driving means to give the machine a stroke of operation.

The return motor bar 150 is depressed with the carriage in its fourth columnar position and this causes the machine to be given a stroke of operation in said column and causes the automatic repeat mechanism to be conditioned for repeating. It is to be noted that this operation of the machine in the fourth column does not cause the platen to be automatically line spaced as did the preceding operation in the fourth column. This is due to the fact that, when the automatic repeat mechanism is conditioned by depression of the return motor bar, the bell crank lever 84—85 is rocked clockwise and the V-shaped lever 116—118 is freed for clockwise movement. The spring 115 acting on link 110 moves the stud 111 into the horizontal portion of slot 112, the V-shaped lever 116—118 being moved by stud 111.

It is to be observed that the conditioning of the machine for operation, which involves reconditioning the repeat mechanism for operation, disables the line spacing connections which are operated by movement of member 113. In other words, the line spacing mechanism is automatically disabled for the second machine operation in the fourth column and it is disabled as an incident to the enabling of the repeat mechanism.

Depression of the return motor bar 150 also

conditions the carriage return mechanism for operation through connections as follows:

The rear end of the link 151, which is rocked by depression of the return motor bar 150 is connected to a downwardly extending link 170 (Figs. 4 and 8) whose lower end is connected to a crank 171 fixed to a shaft 172 extending beneath the machine to the opposite side thereof. Referring to Fig. 10, the opposite end of the shaft 172 has an L-shaped arm 173 fixed to it, which arm is adapted to engage a stud 174 on a pawl 175 pivoted on the end of a lever 176 which, in turn, is pivoted at 177 to a bracket on the machine frame.

Journaled in a bracket 178 (Fig. 12) attached to the base of the machine is a shaft 179 having a crank 180 fixed to it, which crank carries a stud 181 adapted, under certain conditions, to engage the pawl 175. The shaft 179 is rotated by being connected by means of a crank 182 to the wrist pin 60 on the crank 61 that, in turn, is connected to a shaft driven by the motor 55. As the motor operates to give the machine a stroke of operation, the shaft 179 is rotated through one revolution. The shaft starts from the position shown in Fig. 10 and rotates clockwise through one complete revolution.

When the parts are in normal condition with the return motor bar 150 undepressed, the pawl 175 is in the position of Fig. 10 where it is out of the path of the stud 181 so that rotation of the shaft 179 has no effect on the pawl.

When the return motor bar is depressed, the shaft 172 is rocked clockwise as viewed in Fig. 10 which moves the pawl 175 to the position of Fig. 11. Then, after the shaft 179 has rotated through about three-quarters of its revolution, during which time the machine will have been operated through slightly more than one-half of its stroke, the stud 181 engages the pawl 175 and rocks the lever 176 counterclockwise. This occurs after the printing mechanism has operated and results in conditioning the carriage return mechanism for operation so as to start the carriage in its return movement before the machine operation has been completed.

An important advantage of this construction is that the return of the carriage is started before the machine operation is completed instead of waiting for the paper carriage to be released and for it to move over slightly in order to set the return mechanism into operation as has been usual in prior machines. The return operation is speeded up by having it start just after the printing operation is completed. Naturally, it could not start before this, but after an item of a calculation is printed, the carriage can, and does in this machine, start at once.

The lever 176 is connected to a vertical link 185 which, in turn, is connected to a bell crank lever 186 (Fig. 15). The link 185 is urged upward by a spring 187. When the lever 176 is rocked counterclockwise as heretofore explained, the link 185 is pulled downward against the tension of spring 187 to rock the bell crank lever 186 clockwise as viewed in Fig. 15. The upper arm 65 of the bell crank lever 186 is positioned to engage a stud 188 on a slide 189 mounted on a stationary plate 190 at the back of the machine. Pivoted to this slide 189 at 191 is an irregular-shaped member 192 urged clockwise by its spring 193. This pivoted member is normally prevented from moving clockwise by a stud 194 on plate 190 but, when the slide 189 is moved to the right, as viewed in Fig. 15, the pivoted member 192 is moved to the right far enough to position a notch 75

195 in it under the stud 194 so that the pivoted member 192 is free to be moved a limited distance by spring 193. The free end of the pivoted member 192 has an abutment face 196 positioned under a stud 197 on a clutch lever 198 pivoted at 199. When the pivoted member 192 is moved up by the spring 193, the abutment 196 engages stud 197 and rocks the clutch member 198 counterclockwise as viewed in Fig. 15, or clockwise as viewed in Fig. 16. This results in moving a clutch member 200 downward into engagement with a rotating gear 201 of the carriage return mechanism. The latter mechanism is thus set into operation to return the carriage toward its right-hand position as viewed from the front.

The clutch lever 198 is normally prevented from being moved by a member 203 (Fig. 16) pivoted at 204 and urged clockwise by a spring 205. The member 203 has a U-shaped slot 206 engaging over a stud 207 on the end of the clutch member 198. However, when the slide 189 is moved to the right in Fig. 15, which is to the left in Fig. 16, a downward extension 208 on the slide 189 engages a stud 209 on the pivoted member 203 and moves the latter to the released position shown in Fig. 17. In other words, the clutch lever 198 is automatically released at the time that the slide releases the pivoted member 192 for action so that, when the latter member acts, it can move the clutch lever to engaged position.

The carriage return mechanism is automatically disabled after the carriage has been returned a short distance and, in the example illustrated, this distance is slightly more than one columnar space. This disabling is effected by the following mechanism:

Referring to Fig. 15, the rack 220 on the paper carriage supports a bar 221 on which is adjustably positioned a dog 222 having a notch 223 on one of its vertical faces, and an inclined bottom edge 224. As the carriage is being returned, this dog moves from right to left as viewed in Fig. 15 and the notch 223 engages a stud 225 on a pass-by pawl 226 pivoted at 227 to a slide 228. The pass-by pawl 226 is urged counterclockwise by a spring 229. When the carriage is moved in the opposite direction, the inclined cam surface 224 rides over the stud 225 and moves the pass-by pawl 226 against the action of its spring without causing any movement of the slide 228.

The slide 228 is mounted on studs 230 and 231 on the stationary plate 190, the slide being urged to the right as viewed in Fig. 15 by a spring 232. The slide has an upwardly extending projection 233 provided with an abutment face 234 positioned to engage a stud 235 on the pivoted member 192.

As the carriage is returned, the dog 222 engages the stud 225 and moves the slide 228 to the left in Fig. 15. The abutment face 234 engages the stud 235 and rocks the member 192 counterclockwise out of engagement with the stud 197 on the clutch control lever. The portion of the member 192 carrying the stud 235 has a lateral lug 236 (Fig. 16) adapted to engage the rear end of the pivoted member 203. As the member 192 is rocked clockwise from the position of Fig. 17, the member 203 is rocked clockwise and the U-shaped notch 206 in its end engages over the stud 207 on the clutch control lever 198 and cams said lever counterclockwise to disengage the clutch (Fig. 16). This movement also results in moving the slide 189 back to the position of Fig. 15 by reason of the stud 209 on member 203 engaging the projection 208 on the

slide. Return movement of the slide is not hindered by bell crank 186 because link 185 has already been raised by spring 187 to rock the bell crank out of the way. The return movement of slide 189 moves the notch 195 in member 192 from beneath stud 194 so that member 192 is blocked against upward movement.

Briefly stated, the dog 222 on the carriage actuates elements that constitute a disabling mechanism for disabling the carriage return by disengaging the carriage return clutch.

The dog 222 is positioned so that this disablement occurs shortly after the carriage has been returned slightly past its third columnar position. When the disengagement of the clutch occurs 15 the carriage is released and it immediately moves in its normal tabulating direction under the influence of its spring drum. This movement is arrested by the tabulating stop 44 (Fig. 13) for the third column and the net result of the return 20 movement just described is that the carriage is stepped from its fourth to its third columnar position.

After the carriage has been returned to its third columnar position, the machine is automatically given a stroke of operation.

It will be recalled that the return motor bar was depressed to give the machine a stroke of operation in the fourth column. This return motor bar conditions the automatic repeat mechanism so that, when the machine was operated in the fourth column, the regular motor bar 62 was not released and, by virtue of the interlock between the regular bar and the return motor bar, the latter was retained in depressed position. 35 These motor bars, therefore, are in depressed position when the carriage reaches the third columnar position.

As the carriage returned from its fourth to its third columnar position, the high point of 40 the roll 91⁴ momentarily moved the lever 90 and thereby moved the automatic repeat slide 80 rearward far enough to release the latch 92 to allow link 66 to raise for another operation of the machine. Immediate raising of this link was 45 prevented, however, by the delayed action mechanism including the lever 105 (Fig. 4). This delayed action mechanism is not released until the carriage comes to a position of rest against the tabulating stop 44 for the third column. In 50 other words, even though the carriage releases the link 66 as the carriage is being returned from the fourth to the third column, this link is not permitted to move upward until after the carriage has been released from the carriage return 55 mechanism and moved against the third column tabulating stop. This assures that the carriage will reach a stationary position in the third column before the machine is given a stroke of operation. After the roller 91⁴ has passed over 60 the high point of the lever 90 the carriage continues to the left in Fig. 20 until the roller 91³ has passed over the high point of lever 90 and the stop dog 46 of Fig. 13 has assumed a position somewhat to the left of the stop 45, at which 65 point the carriage return mechanism is disabled and the carriage will settle back into its third columnar position with the stop dog 46 in its home position against the stop 45 and as the carriage settles back to its third columnar position, 70 the roll 91³ goes over the high point of lever 90 a second time, but this does not change the position of link 66 which is still held by the delayed action mechanism. At the moment the carriage settles to its final third column position, 75

the link 66 is released and the roll 813 moves on to the inclined portion of lever 90 to help hold the repeat mechanism in repeat condition. It is also held in this position by the latched down 5 motor bar 150.

As soon as the link 66 rises, the machine is given a stroke of operation in the third columnar position of the carriage. At the time this operation occurs, the automatic repeat mechanism is still in operative position and the machine operation in the third column will not result in releasing the motor bars but will condition the parts for another automatic repeat operation when the carriage reaches the second 10 column.

During the operation of the machine with the carriage in the third column, the mechanism shown in Figs. 11 and 12 for conditioning the carriage return mechanism for operation is again 15 operated and the carriage return clutch is engaged in the same manner as described in connection with the fourth column. As soon as this occurs the carriage is again moved in a return direction from the third column toward the second column.

As the carriage starts to return from the third column, the dog 222 moves toward the stud 225 (Fig. 15) and it will be readily appreciated that, if some control were not provided, the carriage 20 return mechanism would be automatically disabled immediately and the carriage would settle back to its third columnar position. Provision is made to avoid this and to cause the carriage to be returned to its second columnar position as follows:

The slide 228 is urged to swing downwardly about the stud 230 as a pivot by means of a spring 240. Such movement is normally prevented when the slide is in the position of Fig. 15 by the stud 231 which is in the horizontal portion of the slot 241 in slide 228. The slot 241 has a notch 242 in its upper side and, when slide 228 is positioned so that notch 242 is above stud 231, the slide may be swung a limited distance by spring 240 about stud 230 as a pivot.

During the movement of the slide 228 to the left in Fig. 15 by the dog 222 in the disabling operation heretofore described for the third column, downward movement of the slide 228 under 40 the influence of the spring 240 was prevented by reason of the fact that the notch 242 engaging over the stud 225 held the slide 228 in horizontal position. However, when the dog 222 moved away from the stud 225 as the carriage settled 45 back to its third columnar position, the slide 228 was freed and it was returned toward the right as viewed in Fig. 15 by the spring 232. As the slide moved to the right, the notch 242 came over stud 231 and at this instant the spring 240 50 snapped the slide to the position of Fig. 19 which placed the stud 225 below the path of travel of the dog 222. Accordingly, the slide 228 is in the position of Fig. 19 when the machine is operated in the third column. As the carriage is returned 55 from the third column, the dog 222 will not be effective and the carriage return mechanism will not be immediately disabled.

Even though the slide 228 is always urged to the right (Fig. 15) by spring 233, said slide is freed so that the spring 240 can move it to the Fig. 19 position. In the machine to which the invention is applied there is a lost motion connection between the rack 220, with which dog 222 moves, and the carriage. When the carriage return clutch is disconnected, the spring for urging

the carriage to the right (Fig. 15), which spring is quite strong, acts very quickly on rack 220 and moves it relative to the carriage far enough and with enough rapidity to free slide 228 so that spring 240 can act as the slide is moving back 5 to the right.

It is desired to disable the carriage return mechanism to stop the carriage in its second columnar position. This is accomplished by another dog 243 (Fig. 20) similar to the dog 222. 10 However, if the slide 228 is in the position of Fig. 19, the second dog 243 will not engage it and the carriage return mechanism will not be disabled. Provision is made for automatically restoring the slide 228 to its Fig. 15 position after the dog 222 15 for the third column has passed the stud 225 and before the dog 243 has reached it.

Referring to Fig. 20, the carriage is provided with a cam 250 adapted to engage the end of an arm 251 of a pivoted yoke having another arm 252 connected to a link 253 which, in turn, is connected at its upper end (Fig. 15) to a lever 254 pivoted on plate 190 and urged clockwise by a spring 255 against a limit stud 256. The lever 254 carries a stud 257 adapted to engage a shelf 258 on slide 228. After the dog 222 for the third column has passed the stud 225, and, before the dog 243 for the second column reaches said stud, the cam 250 acts to rock the yoke 251-252 clockwise to pull link 253 downward. This rocks lever 254 counterclockwise and raises slide 228 back to a horizontal position. As soon as the slide reaches this position, its spring 232 moves it to the right slightly and it is held in this position by the stud 231 which is then in the horizontal portion of the slot 241.

The slide 228 is thus automatically reconditioned so that, when the dog 243 for the second column reaches the stud 225, it will engage said stud and move the slide 228 to the left as viewed 40 in Fig. 15 to again disable the carriage return mechanism in the manner heretofore described. This allows the carriage to settle back slightly to engage the columnar stop for the second column. After the carriage reaches this position the machine is again given an automatic operation. The carriage is provided with a repeat roll in the second column so that the automatic repeat 45 mechanism is again maintained in operative position and the parts are conditioned for a repeat 50 operation when the carriage is returned to its first column.

During the operation of the machine in the second column, the carriage return mechanism is again conditioned and the parts act in the manner heretofore described to return the carriage to the first column. The carriage is thus returned step by step from one column to another. The number of columns to which it is returned can, of course, be varied and one or more columns 55 can be skipped by simply omitting a dog such as 222 or 243 for the column where it is not desired to have the carriage stop.

From the above description, it will be clear that when the return motor bar is depressed the machine is set into operation and it continues to go through a series of automatic operations during which the carriage is returned step by step across the machine. The carriage return mechanism is conditioned for operation at each operation of the machine and is then automatically disabled after the carriage has been returned a predetermined distance. After the carriage return is disabled, the carriage settles back to accurate columnar position, the machine is imme- 75

diately operated automatically, the carriage return is again enabled and the cycle is repeated.

A cam slide 259 (Fig. 20) of the same nature as the slides 250, of which there is one for the 5 third, second and first columns, is provided for the fourth column in order to be sure that the slide 228 will be in operative position at the beginning of operations in the fourth column. Ordinarily, there is no need for this slide, but it 10 has been provided for safety. When the carriage is in its fourth columnar position, the cam 259 is over the lever 251 so as to hold the slide 228 in horizontal position.

15 *Skip action during return of carriage*

The description just given has been directed primarily to a construction in which the carriage is stopped at each column during its return. But, as heretofore mentioned, the number of carriage 20 stops 222 for arresting the return of the carriage can be varied so that one or more columns may be skipped. In this manner a "skip-tab" action is obtained during the return movement of the carriage, the whole action taking place automatically 25 and without interrupting the return.

Arresting carriage at an intermediate position and then automatically completing its return

In some types of work it is desirable to arrest 30 the paper carriage at only one intermediate position during its return. Rinsche Patent 1,580,534 shows a construction in which the carriage may be arrested at an intermediate position but the carriage does not complete its return from this 35 position. Instead it reverses again and moves in its normal feeding direction. If a further return movement is desired, the regular motor return bar must be depressed. In the present machine, the carriage may be arrested at an intermediate 40 position, the machine operated, and the return of the carriage is then automatically completed without the attention of the operator.

This is accomplished by providing only one carriage stop 222. The carriage returns until 45 this stop engages the stud 225 whereupon the carriage return mechanism is disabled, as heretofore explained. The repeat mechanism then causes the machine to be given a stroke of operation. During this stroke of operation the carriage return mechanism is again enabled and the 50 carriage return movement automatically completed without any attention from the operator such as depressing a key.

55 *Automatic line spacing after carriage has been returned to first column*

After the carriage has been returned to its first column, it is desired to have the machine given a stroke of operation and then automatically 60 stopped. The platen should be line spaced before a new series of operations is started.

Referring to Fig. 20, the carriage is provided with a cam slide 260 adapted to engage a curved lug 261 on an arm 262 pivoted at 117 (Figs. 3 and 65 4). This lever extends upward and forward to a point where it is provided with an abutment face 264 positioned to engage a stud 265 on a latch 266 pivoted at 114. As the carriage is returned from its second to its first columnar position, the cam 260 rocks the lever 262 clockwise 70 as viewed in Fig. 4 which swings the latch 266 from the position of Fig. 8 to that of Fig. 9. The corner of the shoulder on the lower end of the latch acts on a stud 267 on the V-shaped lever 75 116—118 and rocks said lever to the position of

Fig. 9 where it is held by the latch which has a shoulder that passes over the stud 267. This results in moving the stud 111 on the link 110 into the vertical portion of the slot 112 in the pendant member 113. Accordingly, when the machine is operated with the carriage in its No. 1 columnar position, the pendant member 113 will be rocked in a manner heretofore described and the slide 126 will be moved downward. It will be recalled that this slide enables the line spacing mechanism so that, as the machine is operated, the platen is line spaced automatically. 10

The automatic repeat mechanism must be disabled before the machine is operated in its No. 1 column because it is desired to have the machine stop after it has operated once in this column. Disabling of the repeat mechanism is accomplished by the same mechanism that controls the automatic line spacing in the No. 1 columnar 15 position of the carriage. 20

Referring to Fig. 8, it will be observed that the slide 126, which is moved downwardly as above explained, carries a stud 270 operating in an inclined slot 271 in one arm 272 of a bell crank lever pivoted at 273. The other arm 274 of this bell crank lever has an abutment face 275 (Fig. 25 9) positioned behind a stud 276 on the repeat slide 80 of the automatic repeat mechanism.

At the beginning of the stroke of operation of 30 the machine after the carriage has moved from its second to its No. 1 columnar position, the slide 126 is moved downward. This immediately rocks the bell crank lever 272—274 counterclockwise which pushes the repeat slide 80 back to inoperative position as shown in Fig. 9 with the result that, as the machine is operated in its No. 1 column, the repeat mechanism is disabled, the motor bars 62 and 150 will be released and returned to normal, and operation of the machine 35 will be stopped. This takes place in spite of the fact that the carriage is provided with a repeat roll 91 in its No. 1 column. This repeat roll bears 40 against the lever 90 and normally conditions the repeat mechanism for repeat operation, but the bell crank lever 272—274 operating against the stud 276 can, nevertheless, move the repeat slide 80 back because of the pin and slot connection between the slide 80 and the lever 84. 45

As the machine completes its operation in the 50 No. 1 column, the slide 126 rises to normal which rocks the bell crank lever 272—274 clockwise and releases the repeat slide 80 which immediately moves under the influence of the spring 83 back to operative position. This insures that the automatic repeat mechanism is again conditioned 55 for repeat operations for the next operation in the No. 1 column which is the first operation of the next series.

From the above description it should be clear 60 that, when the carriage returns to its No. 1 columnar position, the carriage conditions a mechanism that automatically line spaces the platen and automatically disables the repeat mechanism as the machine is operated. The repeat mechanism is 65 disabled even though the carriage has a repeat roll which tends to maintain the repeat mechanism in enabled condition.

It should be observed that, during the first machine operation after the carriage is returned to 70 its No. 1 columnar position, the line spacing mechanism is disabled as an incident to the disablement of the automatic repeat mechanism because the disablement of the automatic repeat mechanism results in the motor bar 150 being released 75

and the release of this bar causes the parts 151, 162, 111, etc., to disable the line spacing mechanism.

As the machine completes its first operation in the No. 1 column after the carriage return, the repeat mechanism is again enabled and the line spacing mechanism disabled. During this operation the motor bars 62 and 150 are released as heretofore mentioned. Stud 156 moves upward and allows spring 159 to rock lever 157 clockwise from the position of Fig. 8 to that of Fig. 4. The rear end of lever 157 rocks lever 162 counterclockwise and the squared bent end of lever 162 engages stud 265 on latch 266 to move said latch from its Fig. 9 position to the position shown in Fig. 4. This releases the bell crank lever 116-118 which is free to move clockwise (Fig. 9) to release stud 111 on link 110. The link 110 then moves upward and positions stud 111 in the horizontal portion of slot 112 so that, upon the next operation of the machine, the slide 126 will not be moved downward. Accordingly, during the second machine operation with the carriage in its No. 1 columnar position, the line spacing mechanism will not be operated and the repeat mechanism will not be disabled.

Non-add control

As previously mentioned it is not desirable to add an item into the register each time the machine is operated in the various columns where the same item is to be repeatedly printed. On the other hand the item must be added into the register during one of the operations.

In order to properly control this operation the machine is provided with a non-add roll in each of the four carriage positions, these rolls being numbered (Fig. 20) 280, 281, 282 and 283. These rolls are adapted to engage the arm 30 of yoke 29 which swings the lever 25 (Fig. 10) to control the members 24 and 22 to disable the pass-by pawl 19 to prevent the register from being rocked into engagement with the actuator racks at the beginning of the return stroke of the machine.

Assume that operations are started with the paper carriage in its right hand position as viewed from the front of the machine, that is, its No. 1 column. The machine is non-added in the first three columnar positions of the carriage because of rolls 280, 281 and 282. The non-add roll 283 for the fourth column is active but provision is made for disabling the non-add control in the fourth column for the first operation of the machine in this column but not for the second.

It will be recalled that when the carriage is moved from its third to its fourth columnar position, the mechanism for automatically line spacing the platen is conditioned for operation and it is conditioned by the downward movement of the slide 126. This downward movement of the slide 126 causes a link 134 on the rear of the machine (Fig. 13) to move to the right as viewed in said figure. This link carries a stud 284 positioned to engage one arm 285 of a pivoted yoke 286 having another arm 287 connected to an arm 288 forming a part of the yoke 29 of a non-add control. The result is that, during the forward stroke of the machine in the fourth column, the yoke 285-286-287 is rocked clockwise. Referring to Fig. 10, this rocks lever 25 clockwise to its lower dot and dash position there shown. This releases member 24 and spring 23 then moves member 22 to inoperative position. In other words, the non-add control is disabled so that the machine is in "addition" condition when it is operated in the

fourth columnar position of the carriage immediately after the carriage has arrived in this position from the third column and the item that has been printed during the series of repeat operations is added into the register.

When the machine is again operated with the carriage in the fourth columnar position, that is, the first operation before the carriage is automatically returned across the machine, it is not desired to have the item added. This is automatically taken care of as an incident to the enablement of the automatic repeat mechanism which is conditioned to operate the machine by the depression of the return motor bar. When the return motor bar is depressed the lever 162 is rocked to engage and move stud 119 which releases bell crank 118-116 which allows stud 111 to move into the horizontal portion of the slot 112. Accordingly, the slide 126 is not moved downwardly as the machine is operated the second time in the fourth column, and the non-add control is not disabled.

As the carriage is returned to its third, second and first columns, it is not desired to add the item except in one column and arrangement has been made to have this addition take place only when the carriage reaches its first column. This is accomplished by control of the non-add mechanism similar to that just described. In other words, the rolls 283, 282 and 281 are operative to non-add the machine in the fourth, third and second columns. As the carriage moves to its first columnar position the line spacing mechanism is enabled by the carriage cam 260 and its connections 261, 262, etc. During the first machine operation with the carriage in its No. 1 column the slide 126 is moved downward and the non-add controls are disabled as heretofore explained so that the machine is placed in "addition" condition to add the item in the register.

From the above it will be clear that provision has been made for normally non-adding the machine in all the four columnar positions of the carriage, and that this non-add mechanism is disabled during the first machine operation when the carriage reaches its fourth column but not during the second operation which is the first of the succeeding series of operations. Likewise, the non-add control is disabled during the first machine operation after the carriage has been returned from the second to the first column but it is not disabled during the second machine operation with the carriage in the first column. In each case the non-add mechanism is disabled as an incident to the disablement of the repeat mechanism and it is again reenabled when the repeat mechanism is enabled.

Total control

As previously mentioned, the total can be printed four times. This requires that the total-taking means be maintained in operative condition during each of the operations of the machine with the carriage in its different columnar positions.

In order that the total may be printed in each column the register cannot be cleared until the last total has been printed. This means that the operation in the first three columns must be a subtotaling operation while the final operation must be a totaling operation to clear the register.

Referring to Fig. 10, when the total key T is depressed, it will rock a bell crank lever 290 which pulls a link 291 rearward and rocks a shaft 292 counterclockwise. Referring to Fig. 4, this

movement of shaft 292 is a clockwise movement. Fixed to the shaft 292 is an arm 293 having a head 294, which is adapted to cooperate with a square stud 295 on the motor bar lever 63. The 5 arm 293 normally occupies the position shown in Fig. 4. When the total key is depressed the arm is rocked clockwise to the position of Fig. 8. Such movement of the arm would not be possible with the parts in Fig. 4 position as the motor 10 bar 62 is shown depressed in said figure, but, with the motor bar raised, the square stud 295 is above the path of the head 294. As shown in Fig. 4, the stud 295 acts as an interlock to prevent depression of the total key when the motor 15 bar has been depressed.

After the total key has been depressed and the arm 292 with its head 293 has been moved to the Fig. 8 position, the motor bar 62 may be depressed either by actuation of the bar itself 20 or by depression of the return bar 150. In either case, the parts move to the position of Fig. 8 where it will be observed that the arm 293 is blocked against return movement by the stud 295 which is in the path of the head 294 on the arm. 25 In other words, as long as the motor bar remains depressed the total key will be locked in depressed position. It will be recalled that the motor bar remains latched in depressed position during the automatic operations of the machine 30 which means that, if the total key is depressed before a series of operations, and one of the motor bars is then depressed to initiate said series, the total key will remain depressed during the 35 entire series of operation so that each machine operation will be a totaling operation. In subtotaling the register is not rocked out of engagement with the actuator racks at the beginning of the return stroke but is allowed to remain in engagement with them so that, as the 40 racks are raised to normal, the pinions are returned to the position they occupied before totaling.

The control of the rocking of the register into and out of engagement with the actuator racks 45 involves a control of the pass-by pawl 19 in the same manner as in non-adding. For example, if said pass-by pawl 19 is disabled at the beginning of the return stroke of the machine, it will not engage the stud 18 (Fig. 10) at the beginning of the return stroke and the register will not be rocked out of engagement with the actuator racks.

As previously described, the machine is provided with carriage rolls 280, 281, 282 and 283 50 for placing it in non-add condition in each of the columnar positions of the carriage, or, in other words, the carriage normally disables pawl 19 in all the columns. Accordingly, assuming that the total key has been depressed, the pawl 60 19 will be disabled against engagement with the stud 18 in the first, second and third columnar positions of the carriage and the register will remain in engagement with the actuator racks both during their descent and ascent so that the 65 operation becomes a subtotaling operation.

But one totaling operation would clear the register and the next one would be incorrect. For the purpose of causing the total printing operations in each column, except the last column of 70 any series of operations, to be subtotaling operations, use is made of the control of the non-add mechanism just described.

It will be recalled that totaling printing is 75 performed by allowing the register to remain in engagement with the actuator racks during their

descent which is during the forward stroke of operations of the machine. The racks and type bars are then differentially positioned by the register pinions which are stopped in "0" position. The register is then rocked out of engagement with the actuator racks at the beginning of the return stroke of the machine, leaving the register pinions in "0" position.

However, when the carriage moves from its third to its fourth column, and during the first 10 machine operation, the automatic repeat mechanism is disabled under control of the carriage and, as an incident to this, the non-add mechanism is disabled as previously described. This makes the pass-by pawl 19 active at the beginning 15 of the return stroke in the fourth column with the result that the register is rocked out of engagement at the beginning of the return stroke and the operation becomes a totaling operation instead of a subtotaling one.

In this manner the register is cleared during the last operation of a series ending with the carriage in the fourth column.

The same sort of control operates when the carriage is being returned from its fourth 25 through its third and second to its first column. During the second operation of the machine in the fourth column, that is, the first operation for the series of operations starting in column No. 4, the line spacing mechanism is not enabled 30 and the operation becomes a subtotaling one because the carriage roll 283 is active. This continues through the third and second columns but, during the first machine operation when the carriage moves from its second to its first column, 35 the automatic line spacing mechanism is again enabled which disables the non-add control so that the operation, assuming the total key has been depressed, is a totaling operation instead of a subtotaling one. This clears the register during the last operation of the series of totaling operations, ending with the carriage in No. 1 40 column.

Operation

While the operation should be clear from the description already given, a brief résumé will be made so that the machine can be visualized without the picture being confused by a multitude of details.

Assume that the carriage is in its normal starting position at the right-hand side of the machine, viewing the machine from the front. This position is referred to in the description as the "first" or "No. 1" columnar position of the 55 carriage.

The operator enters an item on the amount keys and depresses the regular motor bar 62. This causes the item to be printed and, near the end of the machine operation, the paper carriage automatically tabulates to its "No. 2" columnar position. The item is not added in the register because a non-add roll on the carriage has placed the machine in non-add condition before the operation. Also, when the carriage 65 was in its "No. 1" columnar position, it conditioned the automatic repeat mechanism for a repeat operation with the result that, after the carriage is tabulated to its second columnar position, the machine is given a second stroke of operation to again print the item that was entered on the amount keys. This second operation cannot take place until the paper carriage has settled into its correct No. 2 columnar position 70 75

because of the delayed action mechanism controlled by the carriage.

These operations are repeated through the second and third columns and the item is printed in both columns.

As the carriage moves from its third to its fourth column the automatic repeat mechanism is disabled. This does not prevent an operation of the machine in the fourth column but results in automatically stopping the machine after it has operated once with the carriage in the fourth column. The disablement of the automatic repeat mechanism results in conditioning the line spacing mechanism for operation and the platen 10 is automatically line spaced during the latter part of the machine operation in the fourth column. As an incident to the disablement of the repeat mechanism the non-add mechanism is also disabled so that the item is added in the 15 register during the first machine operation in the fourth column. The machine is then in condition for receiving a second item.

The operator enters the second item on the amount keys and depresses the "return" motor 20 bar. This sets the machine into operation, automatically conditions the repeat mechanism for repeat operations, disables the automatic line spacing so that the platen will not be line spaced by the second machine operation with the carriage in the fourth columnar position, and enables the non-add mechanism.

As the machine operates, the item is printed after which, and before the machine operation is completed, the carriage return mechanism is automatically enabled and the carriage starts to return across the machine. When the carriage reaches a position slightly beyond its third column, the carriage return mechanism is automatically disabled, the carriage is released and it settles back toward its third columnar position, the 30 repeat operation of the machine being delayed until the carriage reaches its accurate position for the column. As the carriage settles to its third columnar position the delayed action mechanism is released so that the automatic repeat mechanism can operate to cause the machine to be given a stroke of operation in the third column. Also, as the carriage settles back to its 40 third column, a portion of the carriage return mechanism is automatically conditioned so that the carriage can pass this mechanism when it starts to return from the third column.

During a machine operation in the third column the automatic carriage return mechanism is again enabled and the carriage is returned toward the second column. The disabling mechanism for the carriage return is automatically conditioned again so that, when the carriage has returned slightly past its second columnar position, the return mechanism is again disabled and the carriage is released to settle back into its second columnar position.

These operations continue through the third and second columns, the machine being automatically non-added during the operations in each of these columns so that the item is not entered in the register but it is printed in each column.

As the carriage returns from its second to its first column, the carriage acts to automatically condition the line spacing mechanism for operation so that during the latter part of the machine operation in the first column the platen will be line spaced to be in position for the next series 75 of operations. The automatic repeat mechanism

is disabled for the first machine operation in this column even though there is a carriage roll that tends to enable said mechanism. The result is that, after the machine is operated in the first column, it automatically stops, but when started again, goes through a series of repeat operations.

The disabling of the repeat mechanism in the first column also resulted in disabling the non-add mechanism so that the item is added in the 10 register during the first machine operation after the carriage returns to the first column.

The operations for totaling are the same except that the total key is depressed before the motor bars are depressed. Depression of either 15 of the motor bars after the total key has been depressed results in locking the total key in depressed position for a series of operations. Normally this would condition the machine for clearing the register at each operation but, by making 20 use of the non-add controls, the totaling operation is converted into a subtotaling operation in the first three machine operations of a series during which the total is printed but remains in the register, after which the machine is changed 25 to perform a totaling operation in the last operation of a series to print the total again and clear the register.

Stated another way, the machine is automatically operated through a series of operations during which the carriage moves step by step from a "starting" position to a "subsequent predetermined columnar position". It is then automatically operated through a series of operations during which the carriage moves step by step from said "subsequent predetermined columnar position" toward said "starting" position and, preferably, is stopped in said "starting" position. Provision is made for automatically causing said machine to add or to take a total only during the 30 first machine operation after the carriage has 40 reached the last columnar position of a given series of operations.

By varying the number of stops on the carriage, a number of columns may be skipped during the return of the carriage, or the carriage 45 may be arrested in only one intermediate position and its return afterwards completed automatically.

I claim:

1. In a machine of the class described, a traveling paper carriage movable across the machine in one direction from a starting position, a power operated carriage return mechanism for returning the carriage across the machine, means associated with said return mechanism to cause said carriage to be arrested in an intermediate position during its return to enable said machine to be operated with the carriage in said intermediate position, and means acting automatically to cause said return mechanism to automatically 55 complete the return of said carriage from said intermediate position after the machine operation in said intermediate carriage position.

2. In a machine of the class described, a traveling paper carriage movable across the machine in one direction from a starting position, a power operated carriage return mechanism, and means for conditioning said machine and said carriage return mechanism to cause said carriage to be automatically arrested at a predetermined intermediate position during its return, means for automatically giving said machine a stroke of operation when in said intermediate position, said first mentioned means including portions causing 60 said carriage return mechanism to automatically 65 complete the return of said carriage from said intermediate position after the machine operation in said intermediate carriage position.

- return said carriage to starting position after said machine operation in said intermediate column.
3. In a machine of the class described, a traveling paper carriage movable across the machine in one direction from a starting position, a power operated carriage return mechanism for returning the carriage to its starting position, an automatic repeat mechanism, means for conditioning said repeat and said return mechanisms to cause said carriage to be returned toward its starting position and automatically stopped during its return at a predetermined intermediate position in which position the machine is automatically given a stroke of operation, said means including portions automatically conditioned during said machine operation to cause said carriage return mechanism to be automatically conditioned to return said carriage from its intermediate to its starting position.
- 20 4. In a machine of the class described, a traveling paper carriage having a tabulating mechanism and movable across the machine in one direction under the control of said tabulating mechanism, said tabulating mechanism being operated as an incident to operation of the machine, a power operated carriage return mechanism, an automatic repeat mechanism, means acting to automatically stop said carriage in an intermediate position during its return in which position said automatic repeat mechanism causes an operation of said machine, and means operated as an incident to the operation of the machine in said intermediate columnar position of the carriage for reconditioning said carriage return mechanism to cause it to complete the return of said carriage across the machine.
- 40 5. In a machine of the class described, a traveling paper carriage movable across the machine in one direction under the control of the tabulating mechanism operated as an incident to operation of the machine, a power operated carriage return mechanism, an automatic repeat mechanism, and means controlled by said carriage for automatically disabling said carriage return mechanism after the carriage has been returned to predetermined distance, said automatic repeat mechanism causing said machine to be given a stroke of operation with the carriage in the position in which it is arrested, and means operating automatically during said operation of the machine to recondition said carriage return mechanism to cause it to automatically complete the return of said carriage across the machine.
- 55 6. In a machine of the class described, a traveling paper carriage movable across the machine in one direction, a power operated carriage return mechanism, automatic repeat mechanism, means controlling said return mechanism to cause it to automatically arrest said carriage in a predetermined intermediate position during the return of the carriage across the machine in which position said automatic repeat mechanism causes said machine to be given a stroke of operation, means for delaying said stroke of operation until said carriage has been correctly positioned in said intermediate position, and means causing said return mechanism to automatically complete the return of said carriage after said machine operation has been completed.
- 60 7. In a machine of the class described, a traveling paper carriage movable across the machine in one direction under the control of a tabulating mechanism, a power operated carriage return mechanism, an automatic repeat mechanism, means for disabling said carriage return mecha-
- nism after said carriage has been returned slightly past an intermediate position where it is desired to arrest said carriage to thereby release said carriage to permit it to move to said intermediate position under the control of said tabulating mechanism, said automatic repeat mechanism causing said machine to be given a stroke of operation with the carriage in said intermediate position, and means for causing said return mechanism to automatically complete the return of said carriage after the operation of the machine in said intermediate position.
- 10 8. In a machine of the class described, a traveling paper carriage movable across the machine in one direction under the control of a tabulating mechanism, a power operated carriage return mechanism, an automatic repeat mechanism, means for disabling said carriage return mechanism after the carriage has moved slightly past an intermediate columnar position on its return movement to thereby release the carriage to permit it to move to said intermediate columnar position under the control of said tabulating mechanism, said automatic repeat mechanism acting to give said machine a stroke of operation in said intermediate position of the carriage, means for delaying said machine operation until said carriage is accurately positioned in said intermediate position, and means causing said carriage return mechanism to automatically complete the return of said carriage after the machine is operated.
- 20 9. A calculating machine having a traveling paper carriage movable across the machine in one direction from a starting position, a power operated carriage return mechanism for returning the carriage in the opposite direction, an automatic repeat mechanism for said machine, and means for conditioning said automatic repeat and said carriage return mechanisms to cause said carriage to be automatically arrested at a predetermined intermediate position during its return in which position the automatic repeat mechanism causes the machine to be given a stroke of operation, said conditioning means including portions acting to automatically recondition the carriage return mechanism to cause it to automatically return said carriage to starting position after said operation has been completed, and means for disabling said automatic repeat and said carriage return mechanisms when said carriage reaches its starting position.
- 30 40 10. In a machine of the class described, a traveling paper carriage movable across the machine in one direction under the control of a tabulating mechanism, a power operated carriage return mechanism, and means acting to automatically disable and enable said carriage return mechanism after it has been set into operation to return the carriage to cause it to automatically return the carriage through a series of steps from one column to another across the machine.
- 45 55 11. In a machine of the class described, a traveling paper carriage movable across the machine in one direction under the control of a tabulating mechanism, a power operated carriage return mechanism including a clutch, and means acting to automatically disengage and reengage said clutch after said carriage return mechanism has been set into operation to return the carriage to thereby cause said carriage to be returned through a series of steps from one column to another across the machine.
- 60 70 12. In a machine of the class described, a traveling paper carriage movable across the machine in one direction under the control of a tabulating

mechanism, a power operated carriage return mechanism, and means controlled by said carriage for automatically disabling and enabling said carriage return mechanism after it has been set into operation to return said carriage to cause it to automatically return the carriage through a series of steps from one column to another across the machine.

13. In a machine of the class described, a power driving means, a traveling paper carriage movable across the machine in one direction under the control of a tabulating mechanism, a power operated carriage return mechanism, and means controlled by said carriage and by said power driving means to automatically disable and enable said carriage return mechanism after it has been set into operation to return the carriage to thereby cause said carriage to be returned through a series of steps from one column to another across the machine.

14. In a machine of the class described having a power driving means, a traveling paper carriage, means for moving the carriage across the machine in one direction, a power operated carriage return mechanism, means for conditioning the machine after the carriage has moved across the machine, to cause said driving means to automatically operate said machine through a series of operations, means acting automatically during each of said automatic machine operations to condition said power return mechanism for returning said carriage, and means controlled by said carriage acting to automatically disable said carriage return mechanism shortly after each reenablement to thereby enable the carriage to be automatically returned in a step by step manner.

15. In a machine of the class described, a traveling paper carriage movable across the machine in one direction under the control of a tabulating mechanism, a power operated carriage return mechanism, an automatic repeat mechanism for said machine, and means for controlling said automatic repeat and said carriage return mechanisms to cause said carriage to be automatically returned across the machine from one column to another in a step-by-step manner and means for giving said machine a stroke of operation in each of the columnar positions to which the carriage is stepped.

16. In a machine of the class described having a printing mechanism, a traveling paper carriage movable across the machine in one direction, a power operated carriage return mechanism, an automatic repeat mechanism, means controlled by the carriage for automatically disabling the carriage return mechanism to arrest said carriage in each of its columnar positions during its return, said automatic repeat mechanism acting to give said machine a stroke of operation to cause printing to take place in each of said columnar positions of the carriage, said carriage return mechanism including portions acting automatically to recondition the carriage return mechanism after each of said printing operations to cause the carriage to return to the next column, and means for automatically disabling said carriage return and said repeat mechanism when said carriage has completed its return across the machine.

17. In a machine of the class described, a traveling paper carriage movable across the machine in one direction, a power operated carriage return mechanism, a series of stops on said carriage for automatically disabling said carriage

return mechanism to arrest the carriage in intermediate positions during its return, means for reenabling said carriage return mechanism, and means for momentarily conditioning said carriage return mechanism to prevent the stop which has just disabled it from being effective and for thereafter conditioning said return mechanism so that the succeeding stop will be effective.

18. In a machine of the class described, a traveling paper carriage movable across the machine in one direction, a power operated carriage return mechanism, a series of stops on said carriage for automatically disabling said carriage return mechanism to arrest the carriage in intermediate columnar positions during its return, means for reenabling said carriage return mechanism, means for conditioning said carriage return mechanism after it is reenabled to render ineffective the stop that has just disabled said return mechanism, and means for conditioning said carriage return mechanism to enable the succeeding carriage stop to be effective to disable said carriage return mechanism.

19. In a machine of the class described, a traveling paper carriage movable across the machine in one direction under the control of a tabulating mechanism, a power operated carriage return mechanism, a series of stops on said carriage for successively disabling said carriage return mechanism to release the carriage to permit it to move under the control of said tabulating mechanism, said carriage return mechanism having portions automatically moving, when the carriage is released, out of the path of the stop that has just disabled said return mechanism, means for reenabling said carriage return mechanism, and means for moving said portions of the carriage return mechanism into position to be engaged by the succeeding stop.

20. A machine of the class described having a traveling paper carriage normally movable across the machine in one direction, a power operated carriage return mechanism for returning the carriage across the machine in the opposite direction, a disabling means for said carriage return mechanism, a stop on said carriage adapted to engage said disabling means to disable said carriage return after said carriage has been returned a predetermined distance, means acting automatically during the next operation of the machine to reenable said carriage return mechanism, said disabling mechanism having portions acting to automatically move it out of the path of said carriage stop to enable said carriage to be returned past the intermediate column where it was stopped, and means for reenabling said disabling mechanism so that it may be operated on by a second stop on said carriage to automatically arrest the return movement of said carriage in a succeeding column.

21. A calculating machine having a general operating means, a power driving means, a traveling paper carriage movable from a starting position across the machine in one direction to different columnar positions, a printing mechanism normally operated during each cycle of operation of said operating means to automatically print on paper supported by said carriage the amount of an item entered or a calculation that has been made, a power operated carriage return mechanism for returning said carriage to its starting position, and means acting automatically during a cycle of operation of said operating means with the carriage in one of said columnar positions to set said carriage return mechanism into opera-

tion after the printing mechanism has operated and before said cycle of operation has been completed to thereby enable said carriage return mechanism to start said carriage on its return 5 while said cycle of operation of said operating means is being completed.

22. A calculating machine having a power driving means, a traveling paper carriage movable from a starting position across the machine from 10 column to column in one direction under the control of a tabulating mechanism, a power operated carriage return mechanism, a manipulative means for causing a machine operation in one of the columnar positions of the carriage, and 15 means conditional by said manipulative means and actuated by said power driving means for setting said carriage return mechanism into operation prior to the completion of said machine operation in said columnar position of the carriage.

23. A calculating machine having a power driving means, a traveling paper carriage movable from a starting position across the machine in one direction to different columnar positions, a 25 printing mechanism normally operated during each calculating operation of the machine to print on paper supported by said paper carriage the amount of an item entered or a calculation 30 that has been made, a power operated carriage return mechanism for returning said carriage to its starting position, manipulative means for conditioning said machine to go through a stroke of operation with the carriage in one of said columnar positions, and mechanism conditioned 35 by said manipulative means acting automatically during said machine operation to set said carriage return mechanism into operation after the printing mechanism is operated and before said machine operation has been completed to thereby enable said carriage return mechanism to start said carriage on its return while said machine operation is being completed.

24. A calculating machine having a power driving means, a traveling paper carriage movable from a starting position across the machine in one direction to different columnar positions, a 45 printing mechanism normally operated during each calculating operation of the machine to print on paper supported by said paper carriage the amount of an item entered or a calculation 50 that has been made, a power operated carriage return mechanism for returning said carriage to starting position, manipulative means for conditioning said machine to go through a stroke of operation with said carriage in one of its columnar positions, and mechanism conditioned 55 by said manipulative means and operated by said power driving means acting automatically to set said carriage return mechanism into operation after said printing mechanism is operated and before the machine operation has been completed to thereby enable said carriage return mechanism 60 to start said carriage on its return while said machine operation is being completed.

25. A machine of the class described having a power driving means, means for controlling said driving means to initiate a plurality of series of operations of said machine, a traveling paper carriage, mechanism for moving the carriage back and forth across the machine, means for conditioning the machine to cause said power driving means to automatically operate it through a series of operations during which the paper carriage, as an incident to the machine operations, 75 is stepped through a series of columnar positions

from a starting columnar position to a predetermined subsequent columnar position, and means for conditioning said machine and said carriage moving mechanism to cause said power driving means to automatically operate the machine through a second series of operations during which the carriage moving means steps the carriage through a series of columnar positions from said subsequent position to said starting columnar position.

26. A machine of the class described having a power driving means, means for controlling said driving means to initiate a plurality of series of operations of said machine, a traveling paper carriage, means for conditioning said machine to cause said driving means to automatically operate it through a series of operations, mechanism acting to automatically step said carriage across the machine from column to column in one direction during said series of operations, 20 means for conditioning said machine to cause said driving means to automatically operate it through a second series of operations, and mechanism acting to automatically step said carriage across the machine from column to column in the opposite direction during said second series of operations.

27. A machine of the class described having a power driving means, means for controlling said driving means to initiate a plurality of series of operations of said machine, a traveling paper carriage, means for conditioning the machine to cause said driving means to automatically operate it through a series of operations, mechanism causing said carriage to be automatically stepped 35 across the machine from column to column in one direction during said series of automatic operations, means for conditioning the machine to cause said driving means to automatically operate it through a second series of operations, and mechanism operated by said power driving means 40 acting to automatically step said carriage across the machine in the opposite direction during said second series of automatic operations.

28. A machine of the class described having a power driving means, means for controlling said driving means to initiate a plurality of series of operations of said machine, a traveling paper carriage, means for conditioning the machine to cause the power driving means to automatically operate the machine through a series of operations, mechanism acting to automatically step the carriage across the machine from column to column in one direction during said series of automatic operations, means for conditioning said machine 55 to cause said power driving means to automatically operate it through a second series of operations, and mechanism controlled by said paper carriage and actuated by said power driving means acting to automatically step said carriage across 60 the machine in the opposite direction when said machine is conditioned for said second series of automatic operations.

29. In a machine of the class described, a traveling paper carriage movable across the machine to a predetermined columnar position a platen on said carriage movably supported for line spacing, mechanism acting to automatically line space said platen during the first operation of the machine after the carriage reaches said predetermined columnar position, and means acting 70 to automatically disable said line spacing mechanism for a second machine operation with the carriage in said predetermined column.

30. In a machine of the class described, a 75

traveling paper carriage movable across the machine to a predetermined columnar position, a platen on said carriage movably supported for line spacing, a normally disabled line spacing mechanism for said platen, means conditioned by said carriage while it is in said predetermined columnar position to cause said line spacing mechanism to be automatically operated as an incident to operation of the machine in said column, and means operable to automatically disable said line spacing mechanism for subsequent machine operation with the carriage in said columnar position.

31. In a machine of the class described, a traveling paper carriage provided with a platen movably supported for line spacing, an automatic repeat mechanism for giving the machine an automatic series of operations, a normally disabled line spacing mechanism for said platen adapted to be operated as an incident to operation of the machine, disabling means for disabling said automatic repeat mechanism in a predetermined columnar position of said carriage, and means operated by said disabling means as an incident to the disablement of said automatic repeat mechanism for enabling said line spacing mechanism to cause said platen to be automatically line spaced during the last operation of a series of automatic operations.

32. In a machine of the class described, a traveling paper carriage provided with a platen movably supported for line spacing, an automatic repeat mechanism for giving said machine a series of automatic operations, a line spacing mechanism conditioned for operation as an incident to operation of the machine in a predetermined columnar position of the carriage, enabling means for enabling said automatic repeat mechanism in said columnar position of the carriage, and means operable by said enabling means as an incident to the enablement of said repeat mechanism for disabling said line spacing mechanism.

33. In a machine of the class described, a traveling paper carriage having a platen movably supported for line spacing, an automatic repeat mechanism for causing the machine to go through a series of automatic operations, a normally disabled line spacing mechanism adapted to be operated as an incident to operation of the machine, enabling and disabling means for said repeat mechanism, means operable by said disabling means as an incident to the disablement of said repeat mechanism for enabling said line spacing mechanism, said latter means being also operable by said enabling means as an incident to the enabling of said repeat mechanism for disabling said line spacing mechanism.

34. In a machine of the class described, a traveling paper carriage having a platen movably mounted for line spacing, a normally disabled line spacing mechanism adapted, when enabled, to be operated as an incident to operation of the machine, means controlled by said carriage for enabling said line spacing mechanism in a predetermined columnar position of the carriage, and means operating automatically as an incident to operation of the machine while said carriage remains in said columnar position for automatically disabling said line spacing mechanism.

35. In a machine of the class described, a traveling paper carriage movable across the machine in one direction, means for returning the carriage across the machine to a predetermined columnar position, a platen on said carriage movably supported for line spacing, a line spacing

mechanism, and means operable as an incident to the operation of the machine with the carriage in the column to which it has been returned for automatically causing said line spacing mechanism to line space said platen during said machine operation, said last named means having provisions for automatically disabling said line spacing mechanism for a succeeding machine operation with the carriage in said column.

36. In a machine of the class described, a traveling paper carriage movable across the machine in one direction, a carriage return mechanism for automatically returning the carriage in the opposite direction to a predetermined columnar position, a platen movably supported on said paper carriage for line spacing, a normally disabled line spacing mechanism, an automatic repeat mechanism adapted to be conditioned to cause a series of automatic operations of said machine during which said carriage is returned to a predetermined columnar position, means acting to automatically enable said line spacing mechanism and disable said automatic repeat mechanism for the machine operation in the columnar position to which the carriage is returned, and means operating automatically during said machine operation as a result of the disablement of said automatic repeat mechanism for automatically disabling said line spacing mechanism after the same has operated.

37. In a machine of the class described, a traveling paper carriage movable across the machine in one direction, a carriage return mechanism, an automatic repeat mechanism operable to cause an automatic series of operations of the machine during which said carriage is returned to a predetermined columnar position, a platen movably supported on said carriage for line spacing, a normally disabled line spacing mechanism, means acting automatically to enable said line spacing mechanism and disable said automatic repeat mechanism for the machine operation in the columnar position to which the carriage is returned, and means operating automatically as an incident to said machine operation in said columnar position to disable said line spacing mechanism after the same has operated.

38. In a machine of the class described, a traveling paper carriage movable across the machine to a predetermined columnar position, a non-add mechanism controlled by said carriage for normally maintaining said machine in non-add condition in said column, means for operating said machine in said columnar position of the carriage, and means operating automatically as an incident to said machine operation for disabling said non-add mechanism to cause said machine operation to be an addition operation.

39. In a machine of the class described, a traveling paper carriage movable across the machine to a predetermined columnar position, a non-add mechanism controlled by said carriage normally maintaining said machine in non-add condition, means for operating said machine in said columnar positions of the carriage, and means controlled by said carriage and actuated by said machine during a machine operation in a predetermined column to disable said non-add mechanism to thereby automatically condition the machine for addition during said machine operation in said predetermined columnar position of the carriage.

40. In a machine of the class described, a traveling paper carriage, means for operating said machine through a series of operations during

which said paper carriage is moved from column to column across the machine, means controlled by said carriage for normally maintaining said machine in non-add condition in each of the 5 columnar positions of said carriage, and means acting automatically in a predetermined columnar position to temporarily disable said non-add mechanism to thereby enable an adding operation to take place in said column.

10   41. In a machine of the class described, a traveling paper carriage, an automatic repeat mechanism adapted to be conditioned to cause said machine to go through a series of operations during which said carriage is moved from column to

15   column across the machine, a non-add mechanism controlled by said carriage to normally maintain said machine in non-add condition in each of said columnar positions, and a mechanism controlled by said carriage acting automatically to temporarily disable said non-add mechanism in a predetermined columnar position of the carriage.

20

42. In a machine of the class described, a traveling paper carriage movable across the machine to a predetermined columnar position, a non-add mechanism normally maintaining said machine in non-add condition in said columnar position of the carriage, means acting automatically to disable said non-add mechanism during the first machine operation with the carriage in said predetermined columnar position, means for causing a second operation of said machine with the carriage in said columnar position, and means operable as an incident to the conditioning of the machine for said second operation for automatically reenabling said non-add mechanism.

43. In a machine of the class described, a traveling paper carriage movable across the machine to a predetermined columnar position, a non-add mechanism normally maintaining said machine in non-add condition, an automatic repeat mechanism, disabling means for disabling said automatic repeat mechanism, and means operable by said disabling means as an incident to the disablement of said repeat mechanism for disabling said non-add mechanism.

44. In a machine of the class described, a traveling paper carriage movable across the machine to a predetermined columnar position, a non-add mechanism normally maintaining said machine in non-add condition, an automatic repeat mechanism, carriage controlled disabling means for disabling said repeat mechanism and means conditioned automatically by said disabling means as an incident to the disablement of said repeat mechanism and operated by operation of the machine for automatically disabling said non-add mechanism.

45. A machine of the class described having a power driving means, means for controlling said power driving means to initiate said machine to perform a plurality of series of operations, a traveling paper carriage movable from column to column across the machine in one direction, a carriage return mechanism for returning the carriage from column to column in the opposite direction, a repeat mechanism for causing the machine to automatically operate through a series of operations during which the carriage is stepped across the machine from column to column to a final column in which the last machine operation of the series takes place, means for conditioning said repeat mechanism to cause a second series of operations during which the carriage is stepped across the machine from column

to column in the opposite direction, the first machine operation of said second series taking place with said carriage in said final columnar position, a non-add mechanism normally placing said machine in non-add condition for each operation in each column, controlling mechanism acting to automatically disable said non-add mechanism during the machine operation of the first series in said final columnar position of the carriage, and means acting automatically to enable said non-add mechanism for the first operation of the next series of automatic operations.

46. A machine of the class described having a traveling paper carriage provided with a platen mounted for line spacing, a normally disabled line spacing mechanism adapted, when enabled, to operate as an incident to operation of the machine, automatic repeat mechanism adapted to be conditioned to cause said machine to go through a series of automatic operations, a non-add mechanism normally maintaining said machine in non-add condition, and a single mechanism controlled by said carriage in a predetermined columnar position thereof for automatically disabling said automatic repeat mechanism for enabling said line spacing mechanism, and for disabling said non-add mechanism.

47. In a machine of the class described, an operating means, a traveling paper carriage movable across the machine to a predetermined columnar position, a sub-totaling mechanism normally maintaining said machine in sub-total condition, an automatic repeat mechanism causing the machine to go through a series of automatic operations, carriage controlled means for disabling said repeat mechanism in a predetermined columnar position of the carriage, and means conditioned automatically by said carriage controlled means as an incident to the disablement of said repeat mechanism and operated by said operating means for automatically conditioning said machine for total taking. 30 35 40

48. A machine of the class described having a power driving means, means for controlling said driving means to initiate said machine into a plurality of series of operations, a traveling paper carriage movable from column to column across the machine in one direction, a carriage return mechanism for returning the carriage from column to column in the opposite direction, a repeat mechanism for causing the machine to automatically operate through a series of operations during which the carriage is stepped across the machine in one direction, means for conditioning said repeat mechanism to cause a second series of operations upon a second initiation by said control means during which the carriage is stepped across the machine in the opposite direction, a sub-totaling mechanism normally conditioning said machine for sub-totaling during each of its operations, and mechanism acting to automatically condition said machine for total-taking during the last machine operation of each of said series of operations.

49. A machine of the class described having a power driving means, means for controlling said driving means to initiate said machine into a plurality of series of operations, a traveling paper carriage movable from column to column across the machine in one direction, a carriage return mechanism for returning the carriage from column to column in the opposite direction, an automatic repeat mechanism for causing the machine to automatically operate through a series of operations upon initiation by said

driving control means during which the carriage is stepped across the machine in one direction, means for conditioning said repeat mechanism to cause a second series of operations upon a 5 second initiation by said driving control means during which the carriage is stepped across the machine in the opposite direction, a sub-totalizing mechanism controlled by said carriage for normally conditioning said machine for sub-totalizing for each of its operations, and mechanism controlled by said carriage for automatically conditioning the machine for total-taking during the last machine operation of each of said series of automatic operations.

15 50. In a machine of the class described, a traveling paper carriage, automatic repeat mechanism adapted to be conditioned to cause said machine to go through a series of automatic operations, means controlled by said carriage for maintaining said automatic repeat mechanism in operative condition in a predetermined columnar position of the carriage, and automatic mechanism acting to temporarily disable said automatic repeat mechanism for the machine operation 20 in said predetermined columnar position to cause the machine to cease operation after it has been operated in said column, said automatic mechanism including portions acting automatically as an incident to said last machine operation to place said repeat mechanism in operative condition 25 for the next machine operation.

51. In a machine of the class described, a traveling paper carriage, an automatic repeat mechanism adapted to be conditioned to cause said machine to operate automatically through a series of operations, means controlled by said paper carriage in a predetermined columnar position thereof for maintaining said automatic repeat mechanism in operative condition, mechanism 30 controlled by said carriage for automatically disabling said automatic repeat mechanism for the machine operation in said predetermined columnar position of the carriage to cause said machine to cease operation in said column, and means operating automatically as an incident to said last machine operation for returning said automatic repeat mechanism to condition for operation when said machine is again set into operation.

52. In a machine of the class described, a traveling paper carriage, an automatic repeat mechanism adapted to be conditioned to cause said machine to go through a series of automatic operations, means controlled by said carriage in a predetermined columnar position thereof for automatically maintaining said automatic repeat mechanism in operative condition, a mechanism conditioned by said carriage in said predetermined columnar position and actuated by said machine for disabling said automatic repeat mechanism to cause operation of the machine to cease after the operation in said column, and means operating as an incident to said last machine operation for conditioning said automatic repeat mechanism to be operative upon the next machine operation in said column.

53. In a machine of the class described, a traveling paper carriage, means operable to move said carriage across the machine in one direction, a tabulating mechanism controlling the movement of said carriage in said direction to enable the carriage to be moved from column to column, power operated carriage return mechanism operable to return the carriage in the opposite direction, and means controlled by mech-

anism functioning during operation of the machine for causing said carriage return mechanism automatically to return the carriage across the machine from one column to another in a step by step manner.

54. A calculating machine having a traveling paper carriage, means operable to move the carriage across the machine in one direction, a tabulating mechanism controlling said movement, a power operated carriage return mechanism, and 10 controlling means controlling said carriage return mechanism to cause it to automatically return said carriage across the machine from column to column in a step by step manner, said controlling means being settable to enable said 15 carriage to automatically skip one or more predetermined columns during said step by step return movement.

55. A calculating machine having a traveling paper carriage, means operable to move the carriage across the machine in one direction, a tabulating mechanism controlling said movement, a power operated carriage return mechanism for returning the carriage in the opposite direction, and controlling means for controlling said carriage return mechanism and said machine to cause said carriage to be returned across said machine from column to column in a step by step manner and said machine to be automatically operated in each column in which said carriage 25 stops, said controlling means being settable to enable said carriage to automatically skip one or more predetermined columns during said step by step return movement.

56. A calculating machine having a traveling paper carriage, means operable to move said carriage across the machine in one direction, a tabulating mechanism controlling said movement to enable the carriage to move from column to column as it moves across the machine, a power 40 operated carriage return mechanism, and means controlled by movement of said carriage for controlling said return mechanism to cause it to operate in conjunction with said tabulating mechanism to automatically return said carriage 45 across the machine from column to column in a step by step manner.

57. In a machine of the class described, a power driving means, a traveling paper carriage, means for moving the carriage across the machine in one direction and for returning it in the opposite direction, a platen on said carriage movably supported for line spacing, line spacing mechanism for said platen, and means controlled by said carriage and operated by said power driving 50 means acting to cause said line spacing mechanism to automatically line space said platen when the carriage reaches the end of its movement in each direction.

58. In a machine of the class described, power 60 driving means, means for controlling said driving means to initiate said machine to perform a plurality of series of operations, a traveling paper carriage having a platen, repeat means causing said machine automatically to go through a series 65 of operations, means operating to move said carriage across the machine from column to column from a starting to a finishing column during said series of operations, means for returning said carriage from column to column across said machine from said finishing column to said starting column, and repeat means acting automatically to enable said machine to operate through another series of operations during said return movement of the carriage, line space mechanism 70 75

for said platen, and means controlling said line spacing mechanism to cause it to automatically line space said platen between the end of one series of operations and the beginning of another.

59. In a machine of the class described, power driving means, means for controlling said driving means to initiate said machine to perform a plurality of series of operations, a traveling paper carriage, a non-add mechanism normally maintaining said machine in non-add condition, an automatic repeat mechanism for causing said machine automatically to operate through a series of operations during which said carriage
- 10 moves from column to column across the machine in a given direction, disabling means acting to automatically disable said repeat mechanism when the carriage reaches the end of its travel in said given direction, means for conditioning
- 15 said repeat mechanism to cause said machine to go through a second series of operations during which said carriage moves from column to column across the machine in the opposite direction, and means operating automatically as said repeat
- 20 mechanism is disabled for automatically disabling said non-add mechanism, said means also operating automatically when said repeat mechanism is reenable to reenable said non-add mechanism.
- 25 60. A calculating machine having a power driving means, means for controlling said driving means to initiate said machine through cycles of operations, an automatic repeat mechanism for said machine, a traveling paper carriage, a tabulating mechanism for stepping said carriage from column to column in one direction during which a cycle of operations is performed, a power operated carriage return mechanism and means cooperatively controlling said tabulating, said repeat, and said carriage return mechanisms in predetermined order to enable said machine automatically to operate through a series of repeat operations with the carriage automatically stepping from column to column in either tabulating or return directions upon proper initiation by the control means for said driving means.

61. A calculating machine having a power driving means, means for controlling said driving means to initiate said machine to perform a plurality of series of operations of said machine, an automatic repeat mechanism for said machine, a traveling paper carriage provided with a platen, a tabulating mechanism for stepping said carriage from column to column in one direction through a series of operations of said machine initiated by said driving means, a carriage return mechanism, a line spacing mechanism for said platen and means controlling said tabulating, said repeat, said carriage return, and said line spacing mechanism cooperatively in predetermined order for causing said machine upon a second initiation automatically to perform a second series of operations while the carriage travels from column to column in the opposite direction and the platen line spaces automatically during the last operation of a series with the carriage moving in either tabulating or return direction.

62. A machine of the class described having a power driving means, means for controlling said driving means to initiate said machine to perform a plurality of series of operations, a traveling paper carriage having a platen, a repeat mechanism for conditioning the machine to cause it automatically to operate through a series of operations during which said carriage is stepped

through a series of columnar positions from a starting position to a predetermined columnar position where the machine is automatically operated and stopped, said repeat mechanism being operable to again condition said machine automatically to operate through a second series of operations upon manipulation of said control means during which said carriage is reversely stepped through a series of columnar positions from said predetermined position to said starting position, and mechanism acting automatically to line space said platen during the first machine operation after the carriage has reached the last columnar position to which it is moved for each series of operations.

63. A machine of the class described having a power driving means comprising a pair of motor bars and associated mechanisms, means for controlling said driving means to initiate said machine to perform a plurality of series of operations, a traveling paper carriage movable across the machine in one direction from column to column, repeat mechanism for conditioning the machine automatically to operate through a series of operations during which said carriage is stepped through a series of columnar positions from a starting position to a predetermined subsequent columnar position where the machine is automatically operated and stopped, said repeat mechanism being operable to again condition said machine upon initiation by one of said bars to cause it automatically to operate through a second series of operations, carriage return mechanism operating automatically during said second series of operations to reversely step said carriage through a series of columnar positions from said subsequent position to said starting position where the machine is automatically operated and stopped, line spacing mechanism acting automatically to line space said platen during the first machine operation after the carriage has reached the last columnar position to which it is moved for each of said series of operations, and means acting to automatically disable said line spacing mechanism when the machine is conditioned to begin the next series of operations beginning in the column in which the carriage was stopped in the preceding series.

64. A machine of the class described having a power driving means, mechanisms for controlling said driving means to initiate said machine to perform a plurality of series of operations, a traveling paper carriage having a platen, said carriage being movable across the machine from column to column in one direction, power operated carriage return mechanism for returning the carriage column to column across the machine in the opposite direction, repeat mechanism for conditioning said machine automatically to go through a series of operations during which the carriage is stepped across the machine in one direction from a starting to a finishing columnar position, said machine being automatically operated in each of the columnar positions in which the carriage is stopped including the finishing columnar position, said repeat mechanism also being operable to condition the machine to go through a second series of operations upon operation of certain of said control mechanisms during which the carriage return mechanism steps the carriage from said finishing position to its starting position, said machine being automatically operated in each of the columnar positions in which the carriage is stopped including the starting columnar position, a line spacing mechanism for

said platen operating automatically to line space said platen during the operation of the machine in the last columnar position of the carriage for either series of operations, and means automatically disabling the line spacing mechanism at the start of each series of operations.

65. In a machine of the class described, a traveling paper carriage, means for operating said machine through a series of operations during which the carriage is moved from column to column across the machine, means for conditioning the machine to perform non-add operations when

operated, means for conditioning the machine to take totals, connections controlled by said carriage for conditioning the non-add means to cause the machine to perform sub-totaling operations and additional mechanism acting automatically and controlled by said carriage for temporarily disabling said non-add mechanism for a portion of the machine operation to condition the machine for total taking in a predetermined columnar position.

ROBERT L. MULLER.
